UNITED STATES PATENT OFFICE.

LUDWIG WILSON, OF CHICAGO, ILLINOIS.

WINDOW-WASHER'S SAFETY DEVICE.

Application filed August 5, 1925. Serial No. 48,362.

The present invention relates to window washer's safety devices and is particularly concerned with terminal couplings for anchors provided upon buildings for securing 5 the window washer's harness at some point on the building adjacent the window.

One of the objects of the present invention is the provision of a novel coupling for window washer's harness which is provided with 10 a pair of openings, each of which is adapted to receive and retain securing lugs of an anchor, one of said openings being adapted to provide a reserve supporting surface in case of fracture of the parts about the other opening, or its supporting lug.

Another object of the invention is the provision of a novel coupling structure having a pair of openings separated by a web, said openings being adapted to receive the lugs 20 and head of an anchor and said coupling being adapted to enclose the heads to prevent any possibility of the clothes or other paraphernalia of the window washer catching upon the heads.

Another object of the invention is the provision of a double safety coupling having means for engagement with a pair of spaced anchor lugs to prevent turning of the coupling and having inclined camming flanges 30 beneath the heads of the anchor for drawing the coupling into firm engagement with the anchor.

Another object of the invention is the provision of a double safety coupling comprising 35 an elongated body having side walls for enclosing the heads of the anchor, an open bottom to receive said heads, a transverse stop wall to engage one of said heads and a resilient latch cooperating with the other head to prevent disengagement of said coupling.

Other objects and advantages of my invention will appear more fully from the following description and from the accompanying drawings in which similar characters of reference indicate similar parts throughout the several views.

Referring to the drawings, Fig. 1 is a front elevational view of my coupling applied to its anchor;

Fig. 2 is a side elevational view of the coupling and anchor showing a medial cross-section of the coupling in coupling position;

Fig. 3 is a view similar to Fig. 2 showing the coupling in the process of removal;

Fig. 4 is a plan cross-sectional view taken on the line 4—4 of Fig. 2;

Fig. 5 is a view in perspective of my anchor.

Referring to Figs. 1 to 3, 1 indicates my anchor in its entirety and 4 indicates the coupling as a whole.

The anchor 1 comprises an elongated flat body 13 having transverse securing flanges 14 and 15 at one end. The body 13 is made flat in order that it may be laid between the 65 courses of brick with the flanges 14 and 15 engaged behind the rear side of adjacent bricks and the transverse yoke 16 exposed on the face of the wall adjacent the side of the window.

The body 13 may also be formed with a plurality of serrations forming shoulders 17 along its edge to better engage the adjacent mortar for securing the anchor.

The yoke 16 preferably extends at right 75 angles to the body 13 and is generally located vertically upon the wall of the building. At each end of the yoke 16 are located lugs 18 and 19 having heads 2 and 3 respectively for retaining the coupling 4.

Other details of construction of the anchor will be explained in connection with the coupling 4 since the spacing of the lugs 18 and 19 have a definite relation to the length of the coupling.

While I have shown a preferred form of anchor, I desire it to be understood that my coupling may be used with any of the numerous types of anchors now on the market, provided its parts are made of proportionate size 90 for the anchor.

The coupling 4 comprises an elongated member having a transverse partition or web 6 which forms a part of two spaced longitudinal walls 5 extending in one direction from the partition, and two similar walls 20 extending in the opposite direction, the walls 5, 20 on each side of the coupling being formed as one continuous piece. The coupling is slotted as at 21, 24 to receive the lugs 18 and 19, respectively, of the anchor, the partition 6 and walls 5 and 20 defining two anchor-receiving openings 22 and 23, and, further, performing the function of a stop for the head 3 of the anchor. The longitudinal walls 5 which extend in one direction from the partition 6 are joined at their ends as at 25 and the walls 20 are likewise joined at their ends by a yoke 26. The connecting portion 25 is of the same depth as the walls 5 and is inturned at its lower edge to provide a stop 7, but the yoke 26 is shallow and only bridges the space between 100 105 110

the upper edges of walls 20 in order that it shall not interfere with the insertion of the head 3 of the anchor.

A pair of flanges 9, of shorter length than the slot 21 of the coupling, define a slot 27 of sufficient width to receive the lugs 18 or 19 on the anchor, and the walls 5 are sufficiently spaced to receive the heads 2 or 3 of the anchor. The flanges 9 terminate at a point 28 sufficiently spaced from the partition or web 6 to permit the insertion of the head 2 in the upper opening and the flanges 9 may be slightly inclined as shown in Fig. 2 in order that they may cam beneath the head 2 to draw the coupling into closer engagement with the anchor.

The partition or web 6 extends the full depth of the walls 5 and 20 and is made of substantial thickness to provide the principal means of support of the coupling upon the anchor. A portion of this web 6 is inclined relative to the slotted face of the coupling and is formed with a slot 29, forming a part of the opening 23, to provide the inclined flanges 8 along each wall 20. By reason of the flanges 8 being inclined, they will cam against the head upon the anchor and draw the coupling into close engagement with the anchor.

The flanges 8 are likewise spaced from each other sufficiently to receive either of the lugs 18 or 19, but not sufficiently to pass the heads 2 or 3 and the walls 20 are sufficiently spaced to receive the heads of the anchor. It will thus be observed that since the base of the coupling is open as at 24 and 28, the heads 2 and 3 may be inserted at these points and the coupling may be slid down with the heads 2 and 3 above the flanges 8 and 9, the lugs 18 and 19 sliding in the slots 27 and 29 between the flanges. During this movement, the inclination of the flanges cams the coupling closer to the anchor until the slotted face of the coupling contacts the yoke 16 of the anchor.

The yoke 26 of the coupling is provided with an aperture 30 adapted to receive a rivet 31 passing through the yoke and a resilient latching member 12. The resilient latching member 12 may consist of a strip of tempered steel extending from the yoke 26 over the partition 6 and projecting into the opening between the walls 5. The upper end 32 of the resilient member 12 is bent down to project between the walls 5 and to form a latch which is both capable of being cammed upward by a lug beneath the end or cammed into closer latching engagement by a lug above it. The latch 12 is provided with a knob 33 for convenience in manipulation of the latch during the removal of the coupling. The partition 6 reinforces and supports the resilient member 12 so that it is practically impossible to unlatch the device except by lifting the latch by means of the knob 33. In other words, the partition 6 prevents the latch from being turned in a clockwise direction in Figs. 2 and

3 by excessive force applied to the bent end 32 by a head 2.

The yoke 26 is also provided with an aperture 11 forming a ring 10 which may be used for attaching ropes or straps or other connecting means on the harness of the window washer.

Referring to Fig. 2, it will be noted that when the coupling is in proper position upon the anchor, the lower lug 19 and its head 3 are in engagement with the stop 6 while the upper lug 18 engages the flanges 9 on each side and the flanges are engaged below the head 2. If the length of the yoke 16 on the anchor is such that the upper lug 18 is not in engagement with the stop 7 or connecting portion 25 and if at any time the lower stop 6 should be broken, a reserve supporting means is provided by the upper lug and the stop 7, which may be the means of saving a window washer's life. It should be noted that if a window washer using such a coupling should slip and fall, a terrific strain is put upon the coupling and anchor which might break the lower stop 6 in which event the coupling would still be retained by the upper stop 7. It is, of course, possible to make the single stop heavier according to the usual engineering practice, to withstand any strain desired, but this does not take care of the possible flaws in the metal such as blow holes or cracks which are not apparent upon the usual inspection, and consequently it is not practical in all cases to depend upon the strength of a single retaining stop. The fracture of the first stop will clearly diminish the momentum of the falling body so that the second stop is subjected to much less strain and may be depended upon in an emergency.

The operation of the coupling is as follows:

The heads 2 and 3 may be inserted at the openings 28 and 24 and the coupling slid downward relative to the anchor. During this sliding movement, the lugs 18 and 19 pass between the flanges 9 and 8 respectively, and the heads are engaged above the flanges, the upper head 2 camming the spring 12 upward as shown in Fig. 3, after which the spring snaps behind the head 2. Continued movement of the coupling downward causes the coupling to be cammed against the anchor by the flanges 8 coming to rest when the stop 6 engages the lug 3. The coupling may be removed at any time by lifting the latch by means of the thumb as shown in Fig. 3 and sliding the coupling upward.

It will thus be observed that I have invented a novel coupling having a pair of anchor receiver openings which are adapted to enclose and protect the heads of the anchor in such manner that the clothes of the operator cannot be caught upon the heads.

Although the coupling is supported upon the lower stop by the lower lug, the upper lug also cooperates with the coupling to pre-

vent any twisting movement, to provide a reserve engaging member in case of fracture and to prevent unlatching of the device. The stop for the lower lug also reinforces the resilient latch which may thus be made of greater length and resiliency.

While I have illustrated and described a specific embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A device of the type described comprising a body formed with a pair of openings separated from each other by a web, said web provided with a slot forming a part of one of the openings, and a spring carried by the body and projecting into the other of said openings.

2. A device of the type described comprising a body formed with a pair of openings separated from each other by a web, and either of which is adapted to receive attaching means for the device, said web provided with a slot forming a part of one of the openings, and a stop device carried by the body and projecting into the other of said openings for the purpose defined.

3. In combination with an anchor having a pair of spaced lugs, a coupling having longitudinal walls, spaced pairs of flanges formed on the longitudinal walls, one pair of said flanges extending diagonally transversely of the longitudinal walls, said flanges adapted to be engaged by the lugs when said coupling is positioned in operative position with respect to the anchor, stops formed on the coupling at the ends of said pairs of flanges.

4. A device of the class described, comprising a body formed with an extension and a pair of openings separated from each other by a web, a flange surrounding a portion of one opening, a slot forming a part of the other opening formed in the web, and a spring carried by the body, projecting into one of said openings and supported at a point on its length by said web.

5. A device of the type described, comprising an elongated one piece body formed with an extension extending angularly from one end thereof and a pair of openings in said body separated from each other by an inclined web portion, a flange surrounding a part of one opening, said web provided with a slot forming a part of the other opening, and a spring carried by the body, projecting into one of said openings and supported at a point on its length by the web.

6. In a terminal coupling for an anchor-

ing device, an elongated one piece body having a plurality of openings, flanges projecting into said openings and terminating at a point spaced from one end of each of said openings to admit heads of supporting studs, and spring means supported by said body and projecting into one of said openings to obstruct one of said openings.

7. In a terminal coupling for an anchoring device, an elongated one piece body having a plurality of openings, flanges projecting into said openings and terminating at a point spaced from one end of each of said openings to admit heads of supporting studs, spring means supported by said body and projecting into one of said openings to obstruct one of said openings, and stop means for said spring means.

8. In a terminal coupling for a safety harness, the combination of a coupling having a pair of anchor receiving openings therein, with an anchor having a pair of studs, heads on said studs, and flanges in said openings for engaging beneath said heads.

9. In a terminal coupling for a safety harness, the combination of a coupling having a pair of anchor receiving openings therein, with an anchor having a pair of studs, heads on said studs, and flanges in said openings for engaging beneath said heads, the flanges in one of said openings being inclined to cam said coupling into engagement with said anchor.

10. In a terminal coupling for a safety harness, the combination of a coupling having a pair of anchor receiving openings therein, with an anchor having a pair of studs, heads on said studs, said openings being formed to receive said heads at one end and engage below said heads at the other end, one of said studs being in supporting engagement with the upper end of one of said openings and the other of said studs being spaced from the end of the other of said openings to form a reserve supporting member.

11. In a terminal coupling for a safety harness, the combination of a coupling having a pair of anchor receiving openings therein, with an anchor, engaging members on said anchor to be received in said openings, heads on said members for retaining said coupling, the upper end walls of said openings being spaced a greater distance than the corresponding engaging surfaces of said engaging members are spaced whereby one of said members and openings provides a reserve securing means.

12. In a terminal coupling for a safety harness, a metal member having a pair of openings therein, inwardly extending flanges in said openings, said flanges terminating at a point spaced from one end of each of said openings to receive the heads of an anchor, lateral walls projecting above said flanges, and a yoke connecting said lateral walls, said

yoke having an opening for attaching a harness.

13. In a terminal coupling for a safety harness, a metal member having a pair of openings therein, inwardly extending flanges in said openings, said flanges terminating at a point spaced from one end of each of said openings to receive the heads of an anchor,

longitudinal walls projecting above said flanges, a yoke connecting said longitudinal walls, said yoke having an opening for attaching a harness, and a resilient member carried by said yoke and projecting between said longitudinal walls to form a latch.

In testimony whereof I affix my signature.

LUDWIG WILSON.
